UNITED STATES PATENT OFFICE.

FREDERICK G. FOLBERTH AND WILLIAM M. FOLBERTH, OF CLEVELAND, OHIO.

THERMOALARM.

Application filed May 18, 1927. Serial No. 192,183.

This invention relates to a signal device and is particularly applicable to a device for signaling when the temperature of the cooling fluid of an automotive vehicle engine attains a predetermined point.

An object of the invention is to provide an improved signaling device which will emit an audible signal at predetermined temperatures.

10 Other objects will hereinafter appear.

The invention will be better understood from the description of three practical embodiments thereof, illustrated in the accompanying drawing, in which:—

15 Fig. 1 is a central longitudinal section of one form of apparatus embodying the invention;

Figs. 2 and 3 are central longitudinal sections, taken at right angles, of another embodiment thereof;

Fig. 4 is a central longitudinal section of a third embodiment thereof; and

Fig. 5 is a fragmentary sectional view similar to Fig. 2 of another embodiment.

25 In Fig. 1, an automobile radiator cap is illustrated as comprising a tubular threaded portion 1 adapted to engage the usual threads in the filling spout of an automobile radiator. At the upper end of this tubular section is an 30 outwardly extending flange 2 carrying at its outer edge an upwardly extending tubular wall 3. Secured within and substantially filling the recess above flange 2 and within wall 3 is a capsule, preferably formed of thin 35 metal and having a normally concave upper end or head 5 and a substantially flat lower end or head 6.

The capsule contains a fluid 7 which is so chosen that its boiling point is substantially 40 the temperature which it is desired shall be indicated. The cap is attached to the filling spout of an automobile radiator in the usual manner and, of course, the lower head of the capsule is exposed to the vapors within the 45 radiator.

When the temperature within the radiator reaches that at which the fluid within the capsule vaporizes, vaporization takes place and the expansion thereupon forces the upper head to a convex position as indicated at 50

5', the metal head in the passing from one position to the other emitting a snapping noise clearly audible to the operator of the car.

The external surface of the upper head, 55 when in convex position, is exposed to currents of air, while it is shielded against such currents by wall 3 when in its concave position. This exposure permits the air flowing along the exterior of the head to cool the 60 vaporized fluid therein and cause the same to condense, thus reducing the pressure and allowing the head to snap back to its original position. The alternate vaporization and 65 condensation of the fluid will produce a series of audible signals which will be maintained either until the fluid below the head 6 is cooled to a point where vaporization sufficient to move head 5 upwardly ceases, or until the fluid 7 is so heated to a point where the air 70 on the upper head is unable to condense it sufficiently to cause this head to return to its normal position.

In Figs. 2 and 3 we have illustrated a signaling device in which the signal is produced 75 by the ringing of a bell.

The radiator cap is shown as consisting of a threaded tubular section 6, adapted to be detachably connected with the threads of the radiator filling spout, and provided at its upper end with an outwardly extending flange 7 and an inwardly extending flange 8. Within the tubular section is secured a capsule 9 filled with a suitable liquid or a mixture 80 of liquids which will vaporize at the temperature which it is desired to indicate, and so formed that such vaporization will move its upper end or head upwardly an appreciable 85 distance.

Within the central aperture of flange 8 is 90 secured the lower end of a post 10, this end being provided with a flange 11 seating upon the upper surface of flange 8 and a hollow threaded shank 12 projecting through the aperture of flange 8 and secured therein as 95 by nut 13.

The post may be conveniently made as illustrated with its upper end 14 concentric with the cap and the threaded shank 12, and the remaining intermediate portion offset. 100

The upper end of the post is threaded and a bell 15 is screwed thereon, the margin of bell clearing the outer edges of flange 7, the flange being recessed as at 16, if necessary, to provide ample clearance therefor. Shank 12 is bored and counterbored as at 17 and 18, respectively, and in alignment with the bore 17, which preferably is co-axial with the cap, is an aperture 19 through a supporting arm 20 formed integral with the post. Extending through the apertures 17 and 19 is a longitudinally movable rod 21 carrying at its lower end a disc-like head 22 which rests upon the upper head of capsule 9.

Surrounding rod 21 and extending within the counterbored recess 18, is a helical spring 23 which retains the rod head against the upper end of the capsule.

Near the threaded portion of the post is a lug 24 to which is secured, as by rivets, two downwardly diverging springs 25 carrying at their free ends hammers 26 which may be brought into operative relation with the bell to ring the same.

The operation of this alarm is as follows: When the fluid in the capsule becomes vaporized, the upper end of the capsule is forced upwardly moving with it, head 22 and rod 21. The upper end of rod 21 is forced between the springs 25 just below lug 24 and wedges these springs apart, so that the springs assume the position shown in dashed lines, in Fig. 2, with the hammers closely adjacent the bell 15. Due to the vibration of the vehicle, the hammers at no time when the engine is running, remain absolutely stationary, but are constantly vibrating throughout a small amplitude. This vibration is sufficient to cause the hammers to impinge upon the bell rapidly, causing the alarm to give the audible signal desired.

In Fig. 4 is illustrated a signaling alarm similar to that of Figs. 2 and 3 except that the shape of the bell has been changed and only one hammer is used therewith. In this form the capsule, cap, post, and rod are substantially the same as those already described, but the bell 27, instead of being a surface of revolution, is formed to constitute a shell-like ornament, shown as taking the form of a bird in flight. This shell is secured to the top of post 28 by a screw 29. Supported upon the bell as by rivets 30, is a single spring 31 provided at its free end with a hammer 32. This spring passes over the upper end of rod 33, so that upon the rod being moved upwardly by the vaporization of the fluid within the capsule 34, the hammer is brought closely adjacent the shell 27 and vibrations imparted to the hammer by the vehicle will cause the same to impinge upon the shell and so give out the ringing sound which is to indicate that the undesired temperature has been reached by the motor.

The signal of Fig. 5 is similar to that of

Figs. 2 and 3 except that it is arranged to give an alarm either when the temperature of the motor is below a predetermined minimum or above a predetermined maximum, the signal being silent between these temperatures. In this signal, the rod 35 is provided at its upper end with an enlarged head 36 and the hammer-supporting springs 37 diverge above and converge below this head as shown. It will be seen that whether the rod moves upwards from its normal position, as is the case when the motor becomes too hot, or downwardly, as is the case when the motor becomes too cold, the head will wedge the springs apart, bringing the hammers 38 into bell-ringing position and so producing the alarm.

While we have described the illustrated embodiments of our invention in some particularity, obviously many others will readily occur to those skilled in the art to which this invention appertains, and we do not, therefore, limit ourselves to the details shown and described, but claim as our invention all of the embodiments thereof coming within the scope of the appended claims.

We claim:

1. An indicator for automotive vehicles comprising two elements adapted to emit sounds upon contacting, one of the elements being movable toward and from the other so that in one position the vibrations of the vehicle will cause it to impinge upon the other, and an expansible thermostatic device exposed to the cooling fluid of the vehicle motor, and an extension from said thermostatic means to said first mentioned element moving said elements into a sound producing position.

2. A signal for automotive vehicles having fluid cooled motors, which comprises two elements capable of emitting a sound when moved closely adjacent each other, and a thermostatic device arranged to move one of said elements toward and from the other.

3. A temperature indicator for internal combustion motors which comprises a bell, a hammer therefor, a resilient support for the hammer, and thermo-responsive means associated with the support to move the hammer into ringing relation to the bell.

4. A temperature indicator for internal combustion motors which comprises a bell, a hammer therefor, a resilient support for the hammer so arranged that vibrations from the motor cause the hammer to oscillate, means engaging the support to hold the hammer in bell-ringing position, and thermo-responsive means to move said first mentioned means out of engagement with the support between two pre-determined temperatures.

5. A temperature indicator for internal combustion motors which comprises a bell, a hammer therefor, a resilient support for the hammer so arranged that vibrations from the

car in motion cause the hammer to oscillate, and thermo-responsive means to move the hammer to bell ringing position.

6. A temperature indicator for internal
5 combustion motors which comprises a bell, a hammer therefor, a resilient support for the hammer so arranged that vibrations from the car in motion cause the hammer to oscillate, means engaging the support to hold the
10 hammer in bell-ringing position, and thermo-responsive means to move said first mentioned means out of engagement with the support below a pre-determined temperature.

In testimony whereof we hereunto affix our
15 signatures this 11th day of May, 1927.
